FACE MASK

Howard J. Venaleck, 162 Marble Drive,
Rochester, N.Y. 14615

Filed Sept. 28, 1970, Ser. No. 25,220

Term of patent 14 years

Int. Cl. D24—05; D2—03

U.S. Cl. D83—1

FIG. 1

FIG. 2

FIG. 3

FIG. 4

FIG. 1 is an elevation of a face mask showing my new design;

FIG. 2 is a side elevation of the mask of FIG. 1;

FIG. 3 is a perspective view of the mask of FIG. 1 showing its formation around the face of a wearer and viewed from in front of the face of the wearer; and

FIG. 4 is a rear elevational view of the mask of FIG. 1 as it is shaped to fit over the face of a wearer, and viewed from the face of the wearer.

I claim:

The ornamental design for a face mask, substantially as shown and described.
